UNITED STATES PATENT OFFICE.

WILHELM HERZBERG, OF BERLIN-WILMERSDORF, AND OSWALD SCHARFENBERG, OF BERLIN-SCHONEBERG, GERMANY, ASSIGNEES TO ACTIEN GESELLSCHAFT FÜR ANILIN FABRIKATION, OF BERLIN, GERMANY.

ORTHO-OXYAZO DYES FOR WOOL.

1,426,190.

Specification of Letters Patent. Patented Aug. 15, 1922.

No Drawing.

Application filed November 5, 1921. Serial No. 513,170.

To all whom it may concern:

Be it known that we, WILHELM HERZBERG and OSWALD SCHARFENBERG, citizens of the German Republic, residing at Berlin-Wilmersdorf, Germany, and Berlin-Schoneberg, Germany, our post-office address being Prinzregentenstrasse 10, Berlin-Wilmersdorf, Germany, and Rosenheimerstrasse 12, Berlin-Schoneberg, Germany, have invented 10 certain new and useful Improvements in Ortho-Oxyazo Dyes for Wool, of which the following is a specification.

Our present invention relates to new ortho-oxyazo dyes which may be obtained 15 by combining a polyhalogen-2-diazo-1-oxy-derivative of the benzene series with a sulfonic acid of an amino-oxynaphthalene, the amino group being unsubstituted.

These new dyes form in the dry pulverized shape of their sodium salts dark powders soluble in water with greenish blue color, the aqueous solution becoming violet by addition of sodium carbonate, red by addition of sodium-hydroxide and red-violet by addition of an acid.

The new dyes produce on wool when dyed in an acid bath and treated with chromium mordants or on wool mordanted with chromium mordants greenish blue tints of 30 an excellent fastness to the action of light, to washing and to milling.

In order to illustrate our invention, we give the following examples, the parts being by weight:

35 1. 21.3 parts of 3,4,6-trichloro-2-amino-1-oxybenzene are diazotized by means of 6.9 parts of sodium nitrite and 50 parts of hydrochloric acid of 12° Bé. specific gravity. The diazo-compound is united with a 40 solution of 35 parts of 1-amino-8-oxynaphthalene-2,4-disulfonic acid (monosodium salt), alkaline with sodium carbonate. The dye is worked up as usual. It dyes on wool mordanted with chromium mordants greenish-blue tints, the same shades being obtained by dyeing wool in an acid bath and by treating the tints thus obtained with chromium mordants.

50 2. The diazo-compound of 21.3 parts of 3,4,5-trichloro-2-amino-1-oxybenzene is coupled with 35 parts of 1-amino-8-oxynaphthalene-2,4-disulfonic acid (monosodium salt) in a solution alkaline with sodium carbonate. The dyestuff thus obtained dyes

wool in the like shades as the dyestuff described in example 1.

It is obvious to those skilled in the art that our present invention is not limited to the foregoing examples nor to the details given therein.

What we claim is,—

1. The new ortho-oxyazo dyes which form in the dry pulverized shape of their sodium salts dark powders, soluble in water with greenish-blue color, the aqueous solution becoming violet by addition of sodium carbonate, red by addition of sodium-hydroxide and red-violet by addition of an acid, yielding upon reduction a polyhalogen-2-amino-1-oxy-derivative of the benzene series 70 and a sulfonic acid of a diaminooxynaphthalene, dyeing on wool mordanted with chromium mordants greenish-blue tints, the same shades being obtained by dyeing wool in an acid bath and treating them afterwards with chromium mordants, which dyes may be obtained by combining a polyhalogen-2-diazo-1-oxy-derivative of the benzene-series with a sulfonic acid of an amino-oxynaphthalene, the amino group being unsubstituted.

2. The new ortho-oxyazo dyes which form in the dry pulverized shape of their sodium salt dark powders soluble in water with greenish-blue color, the aqueous solution becoming violet by addition of sodium carbonate, red by addition of sodium-hydroxide and red-violet by addition of an acid, yielding upon reduction a polyhalogen-2-amino-1-oxy-benzene and a sulfonic acid of 90 a diaminooxynaphthalene, dyeing on wool mordanted with chromium mordants greenish-blue tints, the same shades being obtained by dyeing wool in an acid bath and treating them afterwards with chromium 95 mordants, which dyes may be obtained by combining a polyhalogen-2-diazo-1-oxybenzene with a sulfonic acid of an aminooxynaphthalene, the amino group being unsubstituted.

3. The new ortho-oxyazo dyes which form in the dry pulverized state of their sodium salts dark powders soluble in water with greenish-blue color, the aqueous solution becoming violet by addition of sodium carbonate, red by addition of sodium-hydroxide and red-violet by addition of an acid, yielding upon reduction a trihalogen-2-amino-1-

oxybenzene and a sulfonic acid of a diamino-oxynaphthalene, dyeing on wool mordanted with chromium mordants greenish-blue tints, the same shades being obtained by 5 dyeing wool in an acid bath and treating them afterwards with chromium mordants, which dyes may be obtained by combining a trihalogen-2-diazo-1-oxybenzene with a sulfonic acid of an aminooxynaphthalene.

10 4. The new ortho-oxyazo dyes which form in the dry pulverized shape of their sodium salts dark powders soluble in water with greenish-blue color, the aqueous solution becoming violet by addition of sodium carbon-
15 ate, red by addition of sodium-hydroxide and red-violet by addition of an acid, yielding upon reduction a trichloro-2-amino-1-oxybenzene and a sulfonic acid of 1.7-di-amino - 8 - oxynaphthalene, dyeing on wool
20 mordanted with chromium mordants greenish-blue tints, the same shades being obtained by dyeing wool in an acid bath and treating them afterwards with chromium mordants, which dyes may be obtained by
25 combining a trichloro-2-diazo-1-oxybenzene with a sulfonic acid of 1-amino-8-oxynaphthalene.

5. The new ortho-oxyazo dyes which form in the dry pulverized shape of their sodium salts dark powders soluble in water with greenish-blue color, the aqueous solution becoming violet by addition of sodium carbonate, red by addition of sodium-hydroxide and red-violet by addition of an acid, yielding upon reduction a trichloro-2-amino-1-oxybenzene and an 1,7-diamino-8-oxynaphthalene disulfonic acid, dyeing on wool mordanted with chromium mordants greenish-blue tints, the same shades being obtained by dyeing wool in an acid bath and treating them afterwards with chromium mordants, which dyes may be obtained by combining a trichloro-2-diazo-1-oxybenzene with an 1-amino-8-oxynaphthalene disulfonic acid.

6. The new ortho-oxyazo dyes which form in the dry pulverized shape of their sodium

salts dark powders, soluble in water with greenish-blue color, the aqueous solution becoming violet by addition of sodium carbonate, red by addition of sodium-hydroxide and red-violet by addition of an acid, yielding upon reduction a trichloro-2-amino-1-oxybenzene and a 1.7 - diamino - 8 - oxynaphthalene-2.4-disulfonic acid, dyeing on wool mordanted with chromium mordants greenish-blue tints, the same shades being obtained by dyeing wool in an acid bath and treating them afterwards with chromium mordants, which dyes may be obtained by combining a trichloro-2-diazo-1-oxybenzene with 1-amino - 8 - oxynaphthalene-2.4-disulfonic acid. 55 60

7. The new ortho-oxyazo dye which forms in the dry pulverized shape of its sodium salt a dark powder soluble in water with greenish-blue color, the aqueous solution becoming violet by addition of sodium carbonate, red by addition of sodium-hydroxide and red-violet by addition of an acid, yielding upon reduction 3.4.6-trichloro-2-amino-1-oxybenzene and 1.7-diamino-8-oxynaphthalene-2.4-disulfonic acid, dyeing on wool mordanted with chromium mordants greenish-blue tints, the same shades being obtained by dyeing wool in an acid bath and treating them afterwards with chromium mordants, this dye which corresponds as free acid to the formula:

In testimony whereof we affix our signatures in presence of two witnesses. 85

WILHELM HERZBERG. OSWALD SCHARFENBERG.
